CLAIM

(21) Appl. No.: **29/437,050**

The ornamental design for a moisture sensor alarm box with clip, as shown and described.

(22) Filed: **Nov. 13, 2012**

DESCRIPTION

(51) **LOC (9) Cl. 10-04**

FIG. 1 is a front-side perspective view of a moisture sensor

(52) **U.S. Cl.**

alarm box with clip showing my new design;

USPC **D10/56; D10/53**

FIG. 2 is a left-side elevational view thereof;

(58) **Field of Classification Search**

FIG. 3 is a right-side elevational view thereof;

USPC D10/52, 53, 56; 73/23.2, 23.4, 29.01,
73/31.01, 31.05, 73—75, 170.16, 170.17,
73/170.21, 170.26, 335.04; 200/61.04;
324/664, 658, 694; 338/35; 340/500, 501,
340/506, 517, 521, 539.11, 539.26, 539.27,
340/539.28, 545.2, 546, 577, 580, 584, 586,
340/601—605; 702/150

FIG. 4 is a top plan view thereof;
FIG. 5 is a bottom view thereof;
FIG. 6 is a back-side perspective view thereof;

See application file for complete search history.

FIG. 7 is a rear-end elevational view thereof;

(56) **References Cited**

FIG. 8 is a rear-end elevational view of the alarm box of FIG.

U.S. PATENT DOCUMENTS

1 without clip;

D416,201 S * 11/1999 Pinchuk et al. D10/2

FIG. 9 is a front elevational view of the clip of FIG. 6;

FIG. 10 is a rear-end elevational view of the clip of FIG. 6;

FIG. 11 is a side elevational view of the clip of FIG. 6 with the

opposite side of the clip being a mirror image of the side

shown;

FIG. 12 is a top plan view of the clip of FIG. 6; and,

FIG. 13 is a bottom view of the clip of FIG. 6.
